FIG. 1

FIG. 6

FIG. 3

OUR FATHER WHICH ART IN HEAVEN,
Hallowed be thy name.
Thy will be done in earth, as it is in heaven. Forgive us our debts as we have sinned. Lead us not into temptation. But deliver us from evil. For thine is the kingdom, the power, and the glory, forever.

FIG. 4

OUR FATHER WHICH ART IN HEAVEN, Hallowed be thy name.
Thy will be done in earth, as it is in heaven. Give us this day our daily bread. Forgive us our debts as we forgive our debtors.
And lead us not into temptation, but deliver us from evil.
For thine is the kingdom, the power, and the glory, forever. Amen. (MATT 6:9-13)
